UNITED STATES PATENT OFFICE

SAMUEL M. FRIEDMAN, OF TAYLOR, PENNSYLVANIA

BUILDING CONSTRUCTION

Application filed March 29, 1927. Serial No. 179,351.

This invention relates to building construction and more particularly to buildings specially constructed to withstand cave-ins and the like incident to the settling of ground 5 in mining districts.

In certain mining districts, particularly in coal mining regions, the mines have been extended under whole towns and counties. In the course of time the ground settles causing 10 the sinking of houses built thereon. In particular instances houses have entirely disappeared from sight and in other instances the floors of cellars or portions thereof have broken away and fallen in the mines.

15 During the settling of the houses, the ground does not sink uniformly, which causes stress on the houses at different points. This causes the breaking away of joists, the cracking of plaster, the breaking of show window 20 glass and the like, often rendering the houses entirely unfit for occupancy or necessitating a great expense for the repair thereof. The settling of the ground extends over a great 25 period of time, which either makes it necessary to leave the houses in their broken state until the ground has completely settled or to make continuous repairs thereon.

It is therefore one of the salient features 30 of the invention to provide a novel method of building houses for such districts, the invention comprehending novel means for anchoring and bracing the sills of a house together, whereby all of the sills will give or rock together as a single unit, so that the walls of 35 the houses built thereon will not be subjected to uneven stress and thus prevent the cracking of the walls, plaster and the like.

Another object of the invention is the provision of means carried by the sills forming 40 arms for receiving the heads of lifting jacks or the like, whereby the house can be effectively raised into proper even position as the ground gives or sinks.

45 A further object of the invention is the provision of novel means for building a house for mining districts having a cellar or basement, in which the cellar floor is suspended from the girders or sills of the house, so that 50 the cellar floor will be held against movement

in case the ground underneath the floor gives away.

A further object of the invention is the provision of means for forming the cellar floor embodying supporting joists having a 55 wire mesh thereover for receiving a concrete floor, the wire mesh forming means for preventing the breaking of the floor in case of the giving away of the ground, the joists of the cellar being suspended by means of studs or 60 the like from the girders or joists of the first floor.

A further object of the invention is the provision of means of forming the cellar floor and the girders or joists and sills of the first 65 floor of the house independent from the foundation walls of the house, piers being provided between the cellar floor and foundation walls for supporting the girders or under 70 structure of the house, jacks being adapted to be placed between the piers or girders so as to permit the lifting and leveling of the house during the sinking of the foundation 75 walls and ground, the piers also forming means for strengthening the foundation walls 75 for preventing the inward collapsing thereof during the sinking of the ground.

A further object of the invention is the provision of extensions on the floor joists of the house so as to form arms for engaging the 80 ground should the supports for the house give away, the arms being normally supported by studs or posts disposed upon a concrete walk or foundation extending entirely 85 around the house, the arms forming means for supporting a porch or similar structure if desired.

A still further object of the invention is to provide a building structure for mining 90 districts of the above character, which will be durable in use, one that will be simple and easy to construct and one which can be built at a comparatively low cost.

With these and other objects in view, the invention consists in the novel construction, 95 arrangement and formation of parts, as will be hereinafter more specifically described, claimed, and illustrated in the accompanying drawings, in which drawings:

Figure 1 is a top plan view of the frame. 100

work for the bottom floor of a building constructed in accordance with one form of this invention.

Figure 2 is a side elevation of the same showing the framework supported upon suitable piers or the like,

Figure 3 is a fragmentary side elevation of a building constructed upon the framework, showing the position of a jack for raising or trueing the building,

Figure 4 is a detail vertical sectional view showing the method of using face brick in connection with the framework,

Figure 5 is a top plan view partly broken away and in section showing the framework of a further form of my invention,

Figure 6 is a vertical sectional view illustrating the novel formation of the house shown in Figure 5 and the means of constructing the cellar relative to the framework of the house,

Figure 7 is a fragmentary side elevation of a building constructed in accordance with this invention.

Referring to the drawings in detail, wherein similar reference characters designate corresponding parts throughout the several views the letter A generally indicates a framework for a building B, which is constructed in accordance with one form of my invention.

In this form of the invention the framework A comprises longitudinally extending spaced parallel plates 15, which are preferably constructed from structural iron or steel and these plates are connected by cross end plates 16 which are also formed from structural steel or the like. The terminals of the plates 15 and 16 are extended beyond the corners of the frame to provide projecting arm 17, the purpose of which will be later described. Suitable beams or joists 18 are placed upon the cross plates 16 and are bolted to the plates by the use of suitable take up bolts or the like 19. These beams 18 extend beyond the plates as clearly shown in Figure 3 of the drawings. It is to be understood that the steel plates 16 and 17 are rigidly bolted together to form a unitary structure and the same can be braced together in any desired way, such as by the use of diagonally extending corner braces 20 which are riveted or bolted to the plates 16 and 15.

This frame A is placed directly upon suitable piers 21 which can be constructed of any desired material, such as brick, stone or concrete, or the piers can simply consist of wood supporting posts or the like.

After the framework A is constructed as shown the house B is built upon and anchored to the framework and the house is built in the ordinary way according to any desired plan. It can be seen however, that by providing a rigid unitary frame upon which the house is built, that the house will be not sub-

jected to undue strain or stresses should one or more of the piers settle, but the whole house will rock or give as a unit.

As clearly shown in Figure 3 the ends of the beams or joists 18 extend slightly beyond the piers and these ends are adapted to receive jacks or the like 22 whereby the house can be conveniently raised and trued as the piers settle. As the house is raised by means of the jacks suitable wedges or the like can be slipped in between the piers and the frame A.

I prefer to bevel the upper faces of the projecting ends of the beams or sills 18 and these ends can receive suitable boards or the like 23 which forms a substantial cornice around the bottom of the house. This can be used as a ledge for receiving flower pots or the like, or as a bench.

When using face brick for a building, I prefer to provide an upturned flange 24 on the front edges of the plates 15 and 16 and in this instance the plates will be in the nature of angle irons. The first course of face brick 25 is laid directly on the plates and this course will be held in place by the front flange of the plates. The subsequent courses of the bricks are laid directly upon the first course.

In Figures 5 to 7 inclusive I have shown another form of my improved house, which I prefer to consider as the preferred form. This building is generally indicated by the reference character C and can embody a cellar D.

This building C embodies a frame 30 which can be constructed similar to the frame A and embodies longitudinally extending and cross plates or girders 31 and 32. These girders or plates are rigidly connected together and braced in any desired way, such as by diagonal braces 33, to form the rigid unitary structure, which is essential in my building. This frame 30 supports suitable joists 34, upon which are laid and secured to the spaced parallel longitudinally extending floor joists 35 or stringers 35. The ends of these stringers 35 are extended beyond the floor joists 34 a considerable distance to form a plurality of laterally extending supporting arms 36, the purpose of which will be hereinafter brought out.

Any desired type of building is now constructed upon the frame and stringers.

In accordance with usual building construction I provide foundation walls 37 which form the sides for the cellar D. However, in view of the nature of the ground upon which the building is constructed I do not rely upon the foundation walls 37 as a support for the building but in contra-distinction thereto I build a concrete walk 38 entirely around the building and place supporting posts or struts 39 upon the walk and under the ends of the arms 36. If desired

suitable caps 40 can be constructed on the walk for receiving the posts or struts 39.

I also provide at spaced points interior piers 40, which also form a salient feature of this invention. These piers 40 can be constructed from any desired material and of any desired size and are placed against the walls 37, so as to prevent the bulging in of the walls if the ground should sink or settle. 5 These piers terminate short of the frame 30 and if the building starts to settle jacks 41 can be placed in between the frame and the piers so as to raise and true the building, suitable wedges or supporting posts being placed between the piers and the building after the raising of the building. I also prefer to have the upper faces of the piers inclined outwardly so as to prevent the slipping of the jacks and supporting wedges. 10

20 The cellar D is also constructed in a novel manner and I build a framework 42 for the floor of the cellar. This framework can be constructed from suitable floor stringers or the like and are rigidly connected by means of posts or studding beams 43 with the girders or plates 32. Thus the cellar floor is suspended from and supported by the bottom frame of the house.

30 In order to prevent the breaking in or caving of the cellar floor in case the ground should give totally away therefrom I cover the stringers or cellar floor framework 42 with a heavy wire mesh 44 and concrete 45 is then poured thereon forming a substantial 35 floor.

By this construction, it can be seen that the building is formed independent of the foundation walls and that these walls can sink or settle in the ground without effecting the 40 building or the cellar.

It also can be seen that if the building should settle suddenly that the arms 36 will form a wide base for engaging the ground which will increase the area of the building 45 and thus form a support therefor.

The arms 36 can be provided to enhance the beauty of the house or building as well as to serve as supports therefor and it can be seen that a porch 45 can be built thereon, 50 as suggested in Figure 7 of the drawing.

I also prefer to extend the floor stringers 46 of the second story of the house beyond the walls thereof so as to form arms for receiving shoring if necessary and a cornice.

55 Braces or straps 46 can be extended from one floor to the other to prevent the building from collapsing or bulging, if so desired.

From the foregoing description, it can be seen that I have provided a novel building 60 particularly adapted for mining districts in which the collapsing of the building is precluded.

Changes in details may be made without departing from the spirit or scope of this invention, but what I claim as new is:

1. In a building construction for settling ground in mining districts, a supporting framework upon which a building is adapted to be constructed, comprising longitudinal and cross plates rigidly connected together against independent movement, supports for the framework, joists upon the framework projecting beyond the plates and connected thereto, the projecting ends of the supports forming arms adapted to be engaged by lifting jacks to facilitate the raising and leveling of the framework. 70

2. In a building for mining areas, a rigid framework upon which a building is to be constructed, a cellar floor, and means for suspending the cellar floor directly from said framework. 80

3. In a building construction for mining areas, a rigid framework upon which a building is to be constructed, piers independent of said framework, and elevating means adapted to be interposed between the piers and framework. 85

4. In a building construction for mining areas, a rigid framework upon which a building is to be constructed, foundation cellar walls independent of the framework, means for supporting the framework laterally of said walls, and means for raising and trueing the building relative to said walls. 90

5. In a building construction for mining areas, a rigid primary framework movable as a single unit upon which a building is to be constructed, foundation cellar walls independent of the framework, interior piers arranged below the framework and engaging the cellar walls at spaced points to form braces therefor, lifting elements disposed between the piers and framework, and a cellar floor independent of the cellar wall. 100

6. In a building construction, a rigid primary framework movable as a single unit, floor stringers connected with and supported by said framework and projecting laterally thereof, cellar walls arranged below the framework and independent thereof, a concrete foundation walk disposed around said walls, means for supporting the framework engaging the foundation and said floor stringers, a cellar floor independent of said walls, and means for suspending the floor from said framework. 110

7. In a building construction for mining areas, a primary rigid framework movable as a single unit upon which a building is to be constructed, cellar walls arranged below the framework and independent thereof, a cellar floor independent of the cellar walls, means for suspending the floor from the framework, a plurality of supporting piers disposed at spaced points about the cellar walls and in engagement therewith terminating below the upper edge of said walls and below the framework, and means for adjusting the framework on said piers. 120

125

130

8. In a building construction, a rigid primary framework movable as a single unit, floor stringers connected with and supported by said framework and projecting laterally thereof, cellar walls below the framework and independent thereof, a concrete foundation walk disposed around said walls, the stringers projecting over said walk, supporting posts engaging the stringers and walk, a cellar floor independent of the cellar walls, means for suspending the floor from the framework, a plurality of supporting piers disposed at spaced points about the cellar walls and in engagement therewith terminating below the upper edge of said walls and below the framework, and means for adjusting the framework on said piers.
9. In a building construction for mining areas, a primary rigid framework movable as a single unit upon which a building is adapted to be constructed, a cellar floor including floor stringers, a wire screen secured to said stringers, a concrete floor facing supported by said screen and stringers, and studing beams connecting the cellar floor stringers with the framework for supporting the same.

In testimony whereof I affix my signature.
SAMUEL M. FRIEDMAN.
